UNITED STATES PATENT OFFICE.

BENJAMIN F. HUTCHES, JR., OF ALLENDALE, NEW JERSEY.

RIBBON-FEED MECHANISM.

1,033,246.

Specification of Letters Patent. Patented July 23, 1912.

Application filed March 2, 1911. Serial No. 611,812.

To all whom it may concern:

Be it known that I, BENJAMIN F. HUTCHES, Jr., a citizen of the United States, residing at Allendale, county of Bergen, and State of New Jersey, have invented a new and Improved Ribbon-Feed Mechanism, of which the following is a specification.

This invention relates to novel means for advancing the ribbon of typewriters and for automatically reversing its movement after being completely unwound from one of the ribbon carrying spools.

The device is shown to be applied to a so-called "visible" typewriter in which a vertically reciprocable ribbon holder or antenna is arranged in front of the platen. This holder raises the ribbon into the path of the type when a character is to be written, while it lowers the ribbon after the writing of each character to uncover the latter for inspection. This alternate raising and lowering of the ribbon holder is utilized for intermittently feeding the ribbon and for automatically reversing its movement when one of the spools has become exhausted.

In the accompanying drawing: Figure 1 is a vertical cross section through part of a typewriter embodying my invention; Fig. 2 a plan of the ribbon feed mechanism proper; Fig. 3 a vertical longitudinal section on line 3—3, Fig. 2; Fig. 4 a cross section on line 4—4, Fig. 2; Fig. 5 a detail of the feed bar, and Fig. 6 an enlarged cross section on line 6—6, Fig. 2.

The numeral 10 indicates a platen which is hung in the typewriter frame 11 and receives intermittent rotary movement in suitable manner. In front of platen 10 and back of the usual type-guide 12 is arranged a vertically reciprocative antenna or member 13 through recesses 14 of which passes the ribbon 15, the latter being confined to said recesses by upright pins 16. Antenna 13 may receive the necessary movement by any suitable means which do not form part of the present invention. The drawing shows a universal bar 17 so arranged relatively to the type-levers 18 that upon the ascent of the levers, their shoulders 19 will force said bar backward. To

bar 17 is attached one end of a rearwardly extending arm 20, the other end of which is fulcrumed to a swinging arm 21. In a fixed bearing 22 is journaled a two arm lever 23 the upper arm of which carries a pin 24 straddled by a fork 25 that is firmly secured to arm 20 and participates in the horizontal reciprocation thereof. The lower bent arm of lever 23 terminates in a fork 26 that engages a lower transverse pin 27 of antenna 13. Type lever 18 receives its motion by the usual key lever 28 influenced by spring 29 and connected to lever 18 by elbow lever 30. It will be seen that upon each depression of a key, universal bar 17 is shifted backward to tilt lever 23 and thereby raise antenna 13 together with ribbon 15. Upon the release of the key, the parts return to the position shown in Fig. 1, a suitable spring (not shown) shifting bar 17 forward into its position of rest.

The above described vertically reciprocative movement of antenna 13 is utilized in the following manner for feeding the ribbon: To the typewriter frame 11, is secured, by screws 31, a sectional base or holder B, comprising essentially a pair of preferably horizontal plates 32 which are connected by a tube 33 secured to standards 34 of said plates. Into each plate 32 is tapped a vertically extending screw 35 upon which are free to turn a ratchet wheel 36 and a shipping lever 37 located respectively above and below plate 32. Upon the upwardly protruding cylindrical end of each screw 35 is removably fitted a ribbon spool 38 having a pin 39 that engages a corresponding socket 40 of wheel 36 so as to cause the spool and wheel to rotate in unison. To the cores 41 of spools 38 are secured the ends of ribbon 15, the latter being of such a length as to fill a single spool. By slowly and intermittently winding the ribbon upon the other spool, it is drawn over antenna 13 to be passed in front of platen 10 during the writing operation. After the ribbon has been almost completely unwound from one spool, its movement is automatically reversed, which play is repeated until the pigment of the ribbon has been exhausted.

The means for operating the spools in the manner desired, comprise a pair of oscillative two arm feed levers 42 fulcrumed to the lower sides of plates 32 at 43. The 5 inner arm of each lever 42 carries an inclined or wedge shaped abutment 44 which is held in permanent engagement with one of the pins 16 by a spring 45, said pin being preferably provided with an enlarged foot 10 46. From the outer arm of each lever 42 projects forward a springy member 47 carrying a pawl 48 that extends upward through a slot 49 of plate 32 for engagement with the corresponding ratchet wheel 36. 15 The construction is such that pawls 48 engage alternately their respective ratchet wheels, or in other words when one pawl engages its ratchet wheel, the other pawl is thrown out of engagement with its wheel. 20 For this purpose the shipping levers 37 hereinabove referred to are provided, which when swung forward engage members 47 and thereby push pawls 48 out of engagement with their respective ratchet wheels 25 36. Each lever 37 is provided with a preferably sector-shaped arm 50 carrying an eye or guide 51 that projects upwardly through a corresponding slot 52 of plate 32 and through which ribbon 15 is threaded. Arms 30 50 are further provided with apertures 53 accommodating pins 54 that depend from the ends of a shipping bar 55 slidable in tube 33. Bar 55 is provided with a pair of adjoining V-shaped notches 56 that are 35 adapted to be engaged by a tapering detent 57 influenced by a spring 58. Fig. 2 illustrates the position the parts occupy when the ribbon 15 is intermittently fed toward the right (Fig. 2) by the hereinabove 40 scribed vertical reciprocation of antenna 13. As the diameter of the right hand spool 38 gradually increases while that of the left hand spool decreases, eyes 51 will cause their sectors 50 and shipping levers 37 to 45 turn in the direction of the arrows indicated in Fig. 2 and to simultaneously move bar 55 toward the right. When the unwinding of the ribbon from the left hand spool 38 is nearly completed, the rotation of the sectors 50 and the movement of bar 55 will have proceeded to such an extent that detent 57 has been pushed out of one of the notches 56 and has passed the crest between the notches, thereby permitting spring 58 to 50 55 project the detent into the other notch. The sudden movement toward the right thus imparted to bar 55 will cause shipping levers 37 to receive a quick final movement in the direction of the arrows, whereby the right hand pawl 48 is thrown out of engagement with its ratchet wheel 36, while the left hand pawl is simultaneously brought into engagement with its ratchet wheel. The 60 ribbon will now be rewound upon the left

hand spool until the ribbon on the right 65 hand spool has become exhausted, whereupon its movement is automatically reversed in the manner described.

It will be seen that my ribbon feed mechanism is of simple construction and requires 70 but a minimum number of parts for automatically reciprocating the ribbon. The various parts may be assembled without the typewriter and may be quickly set into the latter by tightening screws 31. Owing to 75 the absence of all bevel gears and similar transmissions hitherto generally employed, friction is diminished, so that the manual power necessary for operating the typewriter is considerably reduced. 80

I claim:

1. A ribbon feed mechanism comprising a pair of feed levers, resilient members on said levers, pawls carried by said members, ratchet wheels adapted to be engaged by the 85 pawls, spools removably fitted to the ratchet wheels and adapted to carry a ribbon, shipping levers adapted to engage the resilient members and having sector-shaped perforated arms, ribbon guides carried by said 90 arms, a shipping bar having depending pins that engage the arm-perforations, and means for throwing said bar. 95

2. A ribbon feed mechanism comprising a pair of feed levers, resilient members on 100 said levers, pawls carried by said members, ratchet wheels adapted to be engaged by the pawls, spools removably fitted to the ratchet wheels and adapted to carry a ribbon, shipping levers adapted to engage the resilient 105 members and having sector-shaped perforated arms, ribbon guides carried by said arms, a notched shipping bar having depending pins that engage the arm perforations, and a spring-influenced detent 110 engaging the bar-notches. 115

3. A ribbon feed mechanism comprising a reciprocative member actuated by a typewriter key, a lever having an inclined abutment that is adapted to be engaged by said member, and a ribbon spool operatively connected to said lever. 120

4. A ribbon feed mechanism comprising a reciprocative member actuated by a typewriter key, a pair of levers having inclined abutments that are adapted to be engaged by said member, pawls on said levers, ratchet wheels adapted to be engaged by the pawls, and ribbon carrying spools connected to the ratchet wheels. 125

5. A ribbon feed mechanism comprising a reciprocative member actuated by a typewriter key, a pair of levers having inclined abutments that are adapted to be engaged by said member, pawls on said levers, ratchet wheels adapted to be engaged by the pawls, spools connected to the ratchet wheels and adapted to receive a ribbon, and means con-

trolled by said ribbon for throwing the pawls into or out of engagement with their respective ratchet wheels.

6. In a ribbon feed mechanism, a typewriter frame, a horizontally disposed holder removably secured thereto, a pair of ribbon spools carried by the holder and rotatable in parallelism therewith, a vertically reciprocative ribbon guide, and means actuated by said guide for operating the spools.
